(57) **CLAIM**

The ornamental design for a faucet spray head, as shown and described.

DESCRIPTION

FIG. 1 is a front perspective view of a faucet spray head showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the underside of the sprayer head in FIG. 7 and the remainder of the faucet is for environmental purposes only and forms no part of the claimed design.
